UNITED STATES PATENT OFFICE.

W. B. TREADWELL, OF ALBANY, NEW YORK.

LINING FOR COAL-STOVES AND FURNACES.

Specification of Letters Patent No. 21,707, dated October 5, 1858.

To all whom it may concern:

Be it known that I, WILLIAM B. TREADWELL, of the city of Albany, State of New York, have invented a new and useful 5 Method of Constructing the Lining for the Fire-Chambers of Coal-Stoves and Furnaces; and I declare the following specification, with the drawings attached as part of the same, to be a full and perfect description thereof.

It is well understood to be an important matter in the construction of stoves or furnaces for the burning of anthracite coal in order to obtain the most thorough combustion of the fuel, to line the fire chamber with some nonconducting or slowly conducting substance, in order to keep the heat of the fire concentrated upon itself as much as possible, and that for that purpose fire clay 15 lining, or very thick iron pots are employed. The semifusion of the coal with the clay and their adhesion together or clinkering as it is called is an objection to its use; while on the other hand the iron pot transmits the caloric too rapidly for the best 20 condition of combustion for the coal.

My invention proposes for these, the substitution of metal blocks filled with silicious sand as the substantial lining for the fire chamber, its well known property of transmitting and radiating heat slowly allowing just enough of the caloric to pass into the room, wherein the stove is used, yet not so as to impair the effect of the sufficient concentration of heat in the body of the coal itself 25 to produce thorough combustion. In order to do this and to put the lining into the most convenient form for management, I con-

struct the hollow blocks of metal similar in form to the segments of fire-brick now used 40 to line stoves, and of about the same thickness.

Two kinds are shown in the drawings.

Figure 1 represents that being a segment of a circle (part of its front broken to show 45 the contained sand) for a cylindrical fire box lining. Fig. 2 represents a square prism (also showing the sand) for the lining of any rectangular or flat sided fire box.

They are to be made thin shells to be 50 filled with sand, and to be formed into small blocks, so as to be easily put together like bricks, to form a larger or smaller extent of lining as may be needed. They are made in this way also, to be in a portable form 55 for the facility of sale and transportation separate from the stoves.

I am aware that silicious sand has been used in certain arrangements and combinations for the lining of fire or hot air chambers and therefore I do not claim sand as an article wherewith to line fire chambers but

What I claim and desire to secure by Letters Patent is—

The employment of hollow blocks of metal filled in with silicious sand as a new article of manufacture to be used as a substitute in the place of fire brick for the lining of the fire chambers of stoves and furnaces substantially as set forth and described in the within specification.

WM. B. TREADWELL.
